UNITED STATES PATENT OFFICE.

ADOLPHE BESSAT AND LÉON LOUIS LIÉVENS, OF NANTERRE, FRANCE.

ATTACHMENT FOR PRINTING MACHINES.

Original application filed September 21, 1922, Serial No. 589,693. Divided and this application filed November 23, 1923. Serial No. 676,543.

To all whom it may concern:

Be it known that we, ADOLPHE BESSAT and LÉON LOUIS LIÉVENS, both citizens of the Republic of France, residing at Nan-
5 terre, France, have invented certain new and useful Improvements in Attachments for Printing Machines, of which the following is a specification.

This invention relates to sheet-feeding at-
10 tachments for printing apparatus, and is primarily designed for use in connection with the type of apparatus shown and de-
scribed in our prior application, Serial Num-
ber 589,693, filed September 21, 1922; the
15 present case being a division of such prior application.

The object of our invention is to provide an attachment of the character indicated, embodying certain improved features where-
20 by either single or double sheets may be accurately fed one at a time to the printing mechanism, as hereinafter fully described. Reference may be had to the aforesaid ap-
plication for a complete understanding of
25 the printing mechanism; but as such mecha-
nism forms no part of the present invention, it has not been described in the following specification nor illustrated with accompany-
30 ing drawings, excepting in so far as con-
cerns the roller to which the sheets are fed by the present mechanism and which, in turn, delivers them to the printing mecha-
35 nism. The improved feeding attachment may, however, be also used in conjunction with printing mechanisms other than that disclosed in our prior application, and no limitation to any precise mechanism is, there-
fore, contemplated.

In the drawings:
40 Figure 1 is a longitudinal vertical section of the invention.

Fig. 2 is a plan view thereof but with the cambered bar omitted.

Fig. 3 is a detail view of various addi-
45 tional parts which are used when double sheets are being fed to the printing mecha-
nism.

Referring more particularly to the draw-
50 ings, in which the same numerals are used as in the parent case, the sheet-feeding mech-
anism or apparatus, as shown, comprises a table 86, provided at its opposite sides with fixed rails 87 and 88, and itself se-

cured to the printing apparatus by means of a V-shaped strut 91 which is pivoted at the 55 upper ends of its arms to the under side of the table and is fastened at its apex to the bed of said printing apparatus by a milled or knurled stud 92. This strut 91 acts to securely hold in place a cross-shaft 90 which 60 is included in the printing apparatus and is received adjacent its ends in two slots 89 provided in the lower portions of the enlarged front ends of the rails 87 and 88.

In order to enable paper of different sizes 65 to be used, two paper stops or guide plates 93 and 94 are arranged at the inner sides of the rails and are adjusted by means of milled studs 95 and 96, which are mounted on the outer ends of two horizontal set-screws 97 70 and 98 attached to the central portions of the guides. A third adjustable paper guide plate or stop 99 is arranged transversely of the table at the rear portion thereof, and is held in position by a screw 100 which 75 works in a longitudinal slot 101 formed in the table; the guide 99 engaging the rear edges of the sheets 102 piled on the table, while the guides 93 and 94 engage the side edges thereof, as will be understood. The 80 front edges of the sheets are engaged by a stop plate 103, the end edges of which have a sliding fit in vertical grooves 104 formed in the front portion of the rails 87 and 88; and on the horizontal upper edge of this 85 stop are mounted two projecting blades 105 which rest upon the uppermost sheet, the arrangement being such, therefore, that the stop and its two blades constitute a follower, the upper edge of which is constantly main- 90 tained level with the uppermost sheet throughout the feeding operation.

Associated with the above-described fol-
lower, there is a pivoted shutter 107 to assist in the feed, which is mounted at its front 95 edge on a horizontal shaft 108 journaled in the ends of the rails; the rear edge of the shutter resting on two pins 106 which project horizontally forward from the front face of stop 103, to which they are affixed, 100 so that as the follower sinks, due to the diminishing of the pile of sheets, the shutter will sink with it. The shutter serves to bridge the space between the follower and the roller 37, (Figs. 1 and 2); said roller 105 feeding the successive sheets into position

to be printed on by the cylinder 1 of the printing mechanism in the manner disclosed in our above-identified prior case, which also describes the mode of operation of both the 5 roller and the cylinder.

The actual feeding of the sheets is effected by means of a rubber roller 123, which rests on the pile transversely of the table and acts to move the topmost sheet, 10 first in a rearward direction to disengage its front end from the blades 105, and then forwardly over the upper faces of said blades, and across the top of the stop 103 onto the shutter or bridge 107 and thence to 15 the roller 37. This roller 123 is operated in the following manner:—A pinion 109 (Fig. 1) which is suitably geared to the printing cylinder, or its shaft, is provided with a stud 110, to which is pivoted one end of a 20 connecting rod 111 detachably secured thereto by a bolt 112 having a head or knob 113. The connecting rod 111 acts to impart a reciprocatory motion to an upwardly-inclined arm 115, secured at its lower end to 25 one end of a horizontal rock shaft 116 journaled in bearings 117 fastened to the under face of the feed table; the opposite end of the rock shaft having secured to it a second upwardly-inclined arm 114.

30 At the upper part of the two arms 114 and 115 are provided two guide notches 118, the purpose of which is to enable a lateral reciprocatory movement to be imparted to a horizontal shaft 119, the ends of which pass 35 through said slots 118 and through horizontal slots 120 (Fig. 1) formed in rails 87 and 88. Shaft 119 has pivoted to it two rearwardly-extending arms 121 and 122; and it is these two arms which carry the 40 previously-mentioned rubber roller 123. A counter-arm 125, provided at its front end with a stop 124 for coaction with a cross-rod 126 which connects the two rails, is pivoted at its said end on shaft 119 adjacent to arm 121, and extends in the same direction as and parallel with that arm; and when the parts 124 and 126 come into 45 engagement, as indicated in Fig. 1, the counter-arm 125 is temporarily locked against movement. This arm 125 is provided with front and rear horizontal slots 128 and 127 which allow shaft 119 and arms 121 and 122 to continue their movement.

50 Roller 123 is normally free to rotate about its axis, but means are provided for periodically locking it against rotation; for a purpose presently to be described; and with that object, said roller has fixed at its ends two ratchets 131 and 135 engageable by oppositely-acting pawls 129 and 134 carried, respectively, by the arms 121 and 122. Pawl 129 is normally engaged by the rear end of the counter-arm 125 and, in consequence, is held in inoperative position; but when arm 60 65 125 is temporarily locked, as above described,

and arm 121 passes rearwardly beyond the same, said pawl 129 is thereby released and is moved by a torsion spring 130 into engagement with ratchet 131. As a result, roller 123 is prevented from rotating, so 70 that during the remainder of the rearward movement of the roller it will carry the topmost sheet 102 with it; and since the rear edge of the sheet is in contact with the rear stop or guide 99, such rearward movement 75 will cause said sheet to buckle upward, thereby disengaging its front edge from the blades 105 on the front stop or follower 103.

After completing its rearward movement or stroke, roller 123 starts to move forward, 80 and is thereupon locked against rotation by the spring-actuated pawl 134 carried by arm 122; said pawl riding idly over the teeth of ratchet 135 during that portion of the rearward movement of the roller in 85 which the pawl 129 was inoperative and the roller, in consequence, was free to rotate. The said roller, due to its being locked, will therefore carry the sheet forward with it; and during the first two centimeters of this 90 movement, which has a total length of about nine centimeters, the counter-arm 125 and its associated parts are returned to normal position by a spring 136. The sheet is thereby caused to pass over blades 105 and the 95 top of follower 103 onto and across the bridge or shutter 107, whence it is engaged by roller 37 and fed into the printing apparatus. At the conclusion of the forward movement, roller 123 commences to move 100 rearward again, turning freely over the then uppermost sheet until pawl 129 is released by arm 125 and engages ratchet 131, whereafter the same operations recur as have previously been described. 105

In order to effect the feeding of double instead of single sheets, a cambered bar or member 137 (Fig. 1) is positioned upon the table 86 slightly in front of and parallel with the rear stop or guide 99, and is held 110 in place thereon by pins 138 which fit in holes 150 in the table. The purpose of this bar is to effect an upward bending of the pile of sheets, as indicated at 133, so as to facilitate the buckling produced by the rearward movement of roller 123 during the time that it is locked against rotation; and it is assisted in such action by a heavy plate or follower 132 (Fig. 3) which is disposed 115 directly against the front face of guide 99 and is slidably connected thereto by two studs 140 that work in vertical slots 139 formed in said guide, the lower edge of the plate resting immediately upon the sheets, as shown. It is to be understood, however, that said bar need only be used under special conditions, as when feeding double sheets, and that at other times it is not used. Hence, while it is shown in Fig. 1 as a part 120 125 130 135 140 of the apparatus therein illustrated, it is not 130

permanently attached to the paper table but may be removed when desired, as indicated in Fig. 2.

A sheet counter 141 (Fig. 2) is mounted at one side of the feed table and is actuated by arm 115 on rock shaft 116 through the intermediary of a connecting rod 142.

We claim as our invention:—

1. Sheet-feeding apparatus, comprising a feed table to support a pile of sheets; a stop for engagement with one end of the pile and adapted to move downward automatically as the height of the pile decreases, said stop having projecting means fixed to it; a pivoted shutter mounted adjacent the stop and resting at one edge on said projecting means; and a device for feeding the sheets one at a time over said stop.

2. Sheet-feeding apparatus, comprising a feed table to support a pile of sheets; a stop plate for engagement with one end of the pile mounted to slide in a vertical plane and provided at its top with blades adapted to rest upon the topmost sheet, said plate moving downward automatically as the height of the pile decreases; projecting means affixed to said plate; a pivoted shutter mounted adjacent said plate and resting at one edge on said projecting means; and a device for releasing the sheets one at a time from said blades and feeding them thereover.

3. The combination, with a feed table to support a pile of sheets, of feeding mechanism for the sheets embodying: a roller positioned transversely of the pile and resting directly thereon, means for moving the roller backward and forward bodily over the pile, pawl-and-ratchet means associated with the roller for locking it against rotation during its bodily movement in each direction and including a pair of reversely-acting pawls normally tending to engage the ratchet means, and means movable into contact with one pawl during a portion of the movement of the roller in one direction, thereby to disengage that pawl and maintain such disengagement for the duration of such contact, but thereafter movable away from said pawl to enable its automatic reengagement with said ratchet means during the remainder of such movement.

4. Sheet-feeding apparatus, comprising a feed table to support a pile of sheets; front and rear stops thereon to engage the corresponding edges of the pile; a removable cambered bar mounted upon the table adjacent the rear stop to produce an upward bending of the pile; a weight slidably engaged with said rear stop and adapted to rest upon the pile; and a device for feeding the sheets one at time over the front stop.

5. The combination, with a feed table to support a pile of sheets, of feeding mechanism for the sheets embodying: a roller

positioned transversely of the pile and resting directly thereon, a carrier for the roller, means for reciprocating said carrier to move the roller backward and forward bodily over the pile, a ratchet fixed to each end of the roller, a pair of oppositely-acting spring-pressed pawls pivoted to the opposite side members of the carrier for engagement with the corresponding ratchets, one pawl being engaged with its associated ratchet during the movement of the carrier in one direction to lock the roller against rotation but riding idly over said ratchet when the carrier moves in the other direction, and means adapted to engage the other pawl and positively hold it out of locking engagement with its ratchet during a portion of the movement of the carrier in the last-named direction but thereafter automatically releasing it to enable such engagement during the remainder of that movement.

6. Sheet-feeding mechanism according to claim 3, in which the pawl-holding and releasing means comprise an arm associated with the adjacent side member of the roller carrier and adapted to engage the pawl and thereby hold it away from the ratchet, means yieldingly connecting said arm and carrier member to enable the former to move with the latter and thereby maintain its engagement with said pawl, and means for stopping said arm at a predetermined point in its travel to withdraw it from engagement with said pawl.

7. Sheet-feeding apparatus, comprising a feed table to support a pile of sheets; front and rear stops thereon to engage the corresponding edges of the pile, the front stop consisting of a plate mounted to slide in a vertical plane and provided at its top with blades which project over the topmost sheet and bear upon the same; and a feeding device embodying a roller positioned transversely of and resting upon the pile, means for moving the roller backward and forward bodily over the pile, and means for automatically locking said roller against rotation during the latter portion of its rearward movement and during the initial portion of the succeeding forward movement, thereby to cause it to carry the topmost sheet with it during such locked periods so as to successively buckle said sheet, disengage it from said blades and then move it forward over the top of said plate and blades; said plate moving downward automatically as the height of the pile decreases.

8. Sheet-feeding apparatus, comprising a feed table to support a pile of sheets; front and rear stops thereon to engage the corresponding edges of the pile; a removable cambered bar mounted upon the table adjacent the rear stop to produce an upward bending of the pile; a weight slidably en-

gaged with said rear stop and adapted to rest upon the pile; and a device for feeding the sheets one at a time over the front stop, embodying a roller positioned transversely of the pile and resting directly upon the same, means for moving the roller backward and forward bodily over the pile, and means for automatically locking said roller against

rotation during predetermined periods in its movements in opposite directions, thereby ¹⁰ to cause it to carry the topmost sheet with it during such locked periods.

In testimony whereof, we affix our signatures.

ADOLPHE BESSAT.
LÉON LOUIS LIÉVENS.
